UNITED STATES PATENT OFFICE.

HARRIS P. HURST, OF SUMMIT, MISSISSIPPI.

ACCELERATING CARTRIDGE.

SPECIFICATION forming part of Letters Patent No. 562,585, dated June 23, 1896.

Application filed March 28, 1892. Serial No. 426,839. (No model.)

To all whom it may concern.

Be it known that I, HARRIS P. HURST, of the town of Summit, county of Pike, and State of Mississippi, have invented a new and useful Improvement in Cartridges; and I do hereby declare that the following is a full, clear, and exact description of the invention, which will enable those skilled in the art to make and use the same, reference being had to the accompanying drawings, forming part of this specification, in which—

Figure 1 is a longitudinal section of my cartridge. Fig. 2 is also a longitudinal section of my cartridge with an aerial torpedo as the projectile for smooth-bore guns. Fig. 3 is a longitudinal section of a projectile (shell) for rifled guns. Fig. 4 is a longitudinal view of projectile, and Fig. 5 of the base-piece, with rear extension, for use with the projectile. Fig. 6 is a longitudinal sectional view of a projectile with the separating column or tube without the base-piece. Figs. 7, 8, and 9 are end views of projectiles.

Similar letters of reference indicate corresponding parts.

My accelerating cartridge has a case of paper, brass, or other suitable material, and secured to the head A is a tube B, containing the primary charge C, which may be placed wholly or in part in the rear extension D of the base-piece E or projectile E', and the secondary or main or accelerating charge G occupies the annular space within the outer case and surrounding the inner tube B.

The projectile E' may be attached to the base-piece E or column or tube D' in any suitable manner—as, for instance, by the shock of the explosion when fired, Figs. 4 and 5, the two being fitted tight and when fired driven together, so as to remain securely affixed as if made of one piece—and the base-piece E may take the place of or carry the rotating band of the projectile, dotted lines, Fig. 5, or the projectile may have secured to it or integral with it the extension or separating column D' D'', and when used with smooth-bore guns the projectile has the rear extension D'' provided with fins or rotating wings H, and in this case a heavy wad or metal disk I is placed over the primary charge C, and the wad or disk I is intended to drop off when the pro-

jectile leaves the bore of the gun when it is fired.

The base-piece E may be arranged to free itself from the projectile when it is discharged from the piece in various ways, as by exploding a cap a in the base of projectile E', when the explosion will drive the base-piece up against the rear of the projectile which fires the small charge c in the chamber e, the gases being confined by the pressure from the propelling charges until the projectile leaves the muzzle of the gun, when the base-piece will be released by the rearward pressure of the gas in chamber e, or the pin i may secure the projectile till it is sheared off in firing and the air-pressure separate them, or a spring may be interposed between the base-piece and projectile; but I do not claim this last-mentioned device for releasing the base-piece, as I am aware it has already been patented by Joseph R. Hawley, of Hartford, Connecticut.

In Fig. 3 I show a shell with a base-fuse to explode or detonate the bursting charge therein. The rear end of this shell inclines inwardly behind the rotating band.

The manner of loading my cartridge is as follows: The cartridge has in its head the usual primer m inserted and communicates through channel n to the primary charge, which may be entirely within the hollow extension of the projectile or base-piece, the rear end being reamed out until a sharp thin gas-check o is formed, and the main charge, being entirely separated thereby, is not fired until the projectile is well under way and only when the rear of the gas-check o is free from the inner tube. An annular disk or wad s may be placed over the main charge.

Many modifications can be made without departing from the scope of my invention—the subcaliber rear extension of the base-piece, Fig. 5, being omitted when the projectile, Fig. 4, is used in single-charged guns, and the independent base-piece may be arranged to be stored in separate pieces and then attached, when used, to any class of projectiles and shells in any suitable manner, as by an overlapping joint, the separate base-piece being adapted to any number of purposes. I do not wish to limit myself to any form of con-

struction or mode or manner of putting base-piece and forward body of projectile or shell together when used.

I do not claim, broadly, in this application 5 the projectile having the elongated rear extension-piece, nor the said projectile provided with a rotating base-piece, nor the projectile having its rear extension-body separate therefrom, nor the projectile having the elongated 10 rear extension-body and means for preventing the forward flow of gas from the primary to the main charge, nor the projectile having a hollow rear extension-body, nor the projectile having a hollow rear extension-body constructed 15 to receive a propelling charge, nor a projectile carrying an elongated rear portion of reduced diameter constructed to telescope with a charge-containing chamber, nor a cartridge with a tube screwed through its head.

20 I claim—

1. A cartridge having a tube containing the primary charge and a main charge outside of said tube, and a separating-body in the tube extending forward to and attachable to the 25 projectile, substantially as described.

2. A cartridge having secured to its base a tube for the primary charge, an accelerating charge without said tube and an independent body in the tube, attachable to the projectile, 30 between the projectile and primary charge, and separating the same from the main charge until the projectile is in motion from firing the primary charge, substantially as described.

3. A cartridge having the inner primary- 35 charge-containing chamber surrounded by the accelerating charge and separated therefrom by the attachable subcaliber extension-body of the projectile, substantially as described.

40 4. A cartridge having the inner primary-charge tube, the main charge without said tube and the projectile with its subcaliber rear extension-body provided with rotating wings, separating the two charges, substantially as described.

45 5. A cartridge having the primary and main charge chambers and the projectile with its subcaliber rear extension provided with rotating wings separating said charges, 50 until fired, and a disk between said rotating wings and said primary charge, substantially as described.

55 6. A cartridge having a primary-charge-containing chamber, and, in the annular space about it, the main charge held in place by a ring, *s*, and the head of the projectile forward thereof, substantially as described.

7. A projectile having a separate body for its base, as *E*, substantially as described, and 60 an attachable forward body and means to

unite and secure said base-piece to the forward body portion of the projectile, substantially as described.

8. A projectile having an elongated subcaliber rear extension-body, said rear extension-body constructed to be driven onto the projectile, when fired, and affixed thereto by the explosion, substantially as described. 65

9. A projectile having an independent body for its base, as *E*, substantially as described, 70 and separate therefrom and attached, when used, to the forward body of the projectile, substantially as described.

10. A projectile carrying a rear extension-body and a chamber between said projectile 75 and said extension-body having a separating charge therein, substantially as described.

11. A projectile having a separable body for its base, as *E*, carrying thereon the rotating band and a forward body attached to said 80 base-piece in front of said rotating band, substantially as described.

12. A projectile composed of two separate parts, a base-piece, as *E*, carrying the rotating band and the forward body portion, when 85 used, joined to said base-piece, substantially as described.

13. A projectile composed of two independent separate parts, a forward body and a rearward body, said rearward body having an 90 elongated subcaliber rear extension-piece, and means to unite the two bodies permanently by the shock of the explosion, substantially as described.

14. A hollow projectile for the bursting 95 charge therein, the rotating band thereon, and the subcaliber hollow rear extension at the base thereof, substantially as described.

15. A projectile provided with a rotating band and having a subcaliber rear extension-body, the base of said projectile, behind the rotating band, inclining inwardly, substantially as described. 100

16. A projectile having a separable body for its base-piece and a subcaliber extension 105 extending rearward therefrom, and a forward body and means to unite the two bodies, substantially as described.

17. A projectile provided with a separable body for its base having at the rear thereof a 110 subcaliber extension-piece, and a forward body and means to unite the two together, the rearward body carrying the rotating band, substantially as described.

In testimony whereof I affix my signature 115 in presence of two witnesses.

HARRIS P. HURST.
